UNITED STATES PATENT OFFICE.

ANGUS R. COOPER AND HUGH J. CARTHY, OF MOBILE, ALABAMA.

CAR DOOR.

Application filed February 2, 1922. Serial No. 533,607.

To all whom it may concern:

Be it known that we, ANGUS R. COOPER and HUGH J. CARTHY, citizens of the United States, residing at Mobile, in the county of 5 Mobile, State of Alabama, have invented certain new and useful Improvements in Car Doors; and we do hereby declare the following to be a full, clear, and exact description of the invention, such as will enable 10 others skilled in the art to which it appertains to make and use the same.

This invention relates to new and useful improvements in car doors and particularly to box car doors.

15 One object of the invention is to provide a car door which is especially designed for use in connection with refrigerator cars, and which has novel and improved means for hanging the door, and means for moving 20 the door into open and closed position.

Another object is to provide a door of this character which is arranged to fit snugly within the door opening of the car, with means for permitting the door to be 25 moved outwardly beyond the outer face of the car, and then to be moved longitudinally of the car, away from the opening.

A further object is to provide a device of 30 this character wherein the operating mechanism of the door is so constructed and arranged that when the door is in either open or closed position, there will be no projecting parts to be engaged by outside objects, and be broken off thereby.

35 Other objects and advantages will be apparent from the following description when taken in connection with the accompanying drawings.

In the drawings:

40 Figure 1 is an elevation of our improved car door, in closed position.

Figure 2 is an elevation of the same in partially open position, showing the upper portion of the metal plate 16' broken away.

45 Figure 3 is a vertical longitudinal section on the line 3-3 of Fig. 1.

Figure 4 is a horizontal sectional view taken on the line 4-4 of Figure 2, just above the hangers and track.

50 Figure 5 is an enlarged vertical sectional view on the line 5-5 of Figure 2, the closed position being shown in dotted lines.

Figure 6 is a vertical sectional view on the line 6-6 of Figure 2.

55 Referring particularly to the accompany-

ing drawings, 10 represents the side wall of a car, in which is formed a doorway 11. The sides, top, and bottom members of the doorway are beveled and incline inwardly, as shown at 12 and 13, respectively, for engagement of the correspondingly beveled edges 14 and 15, of the door 16. The outer face of the door has secured thereto a metal plate 16', the upper and lower edges of which project from the corresponding edges 14 and 15 of the door, to engage the outer face of the car wall, surrounding the doorway. It will be noted, upon reference to Figures 3 and 6, that it is necessary to move the door vertically, as well as horizontally inward, to 70 properly engage the upper beveled edge 14, inwardly of the beveled portion 12, of the doorway. On the outer face of the car wall, above the doorway, there is mounted the track 17, on which are disposed the rollered 75 hangers 18. Disposed across the lower portion of the outer face of the door is a batten 19, and formed vertically of the door, through the end portions of the batten, are the notches 20. Slidable through these 80 notches 20, are the vertical flat bars 21, disposed against the door, and hinged to the upper ends of these bars are the lower ends of the hangers 18. It will be noted that the 85 hangers extend downwardly for quite a distance on the door, where they are hinged to the bars 21, this permitting sufficient play for the door to move into and out of the doorway. Loops 22, carried by the door, straddle the bars 21, to serve as guides as 90 the door is moved upwardly and downwardly, into closed and open position. Loops 23 straddle the hanger bars 21', adjacent the upper end of the door, but these 95 loops are of greater depth than the loops 22, to permit the hangers to swing outwardly, when the door is being moved into open position. The lower ends of the bars 21 are extended horizontally outwardly, and thence upwardly, as shown at 24, to limit the downward movement of the door, and whereon the door is supported from the hangers, for lateral sliding movement away from the doorway.

In the lower end of the outer face of each 105 side stile of the doorway, there is formed a triangular notch or recess 25, and secured to the door-frame, below each of the notches or recesses, is an upwardly and inwardly curved member 26. Supported for rotary 110

movement by the brackets 27, is a transverse shaft 28, the intermediate portion of which is formed with an angular loop 29, forming a handle, whereby the shaft may be rotated. 5 Each end of the shaft 28 is turned downwardly at right angles, as at 30, and the terminals of the portions 30 are turned to extend horizontally outwardly in opposite directions, as shown at 31. These ends 31 are 10 engaged behind the curved members 26, when the door is in closed position, and into the upper ends of the recesses 25, when the door is in open position. Pivotally mounted on the outer face of the door, above the 15 central crank portion 29, is a hasp 32, which is arranged to be swung down across the said crank portion, and receive the staple 33 through its other end, a pin, or lock 34 being passed through the staple. 20 Extending longitudinally and centrally of the outer face of the door, is a vertical rod or shaft 35, the lower end of which extends through a notch 36, in the intermediate portion of the batten 19, and is turned at right 25 angles, where it is provided with a hand-grip 37. The upper end of the rod 35 is extended at right angles inwardly, at 38, toward the wall of the car, and the terminal of this portion is extended downwardly between 30 the wall of the car and the track 17. It will be noted that the crank portion 38 extends in a direction opposite to that of the lower end 37, whereby when the portion 37 lies flatly against the door, the portion 38 35 will lie in approximately the same position. When the handle 37 is swung outwardly from the door, the crank portion 38 will engage with the wall of the car, and cause the door to swing out of the door way, and 40 away from the car wall, with the result that the door will slide downwardly on the bars 21, until stopped by the ends 24, when the door will be suspended in a vertical position on the hangers 18. The door may then be

readily moved laterally away from the door- 45 way.

When the shaft 28 is rocked, by swinging the central portion 29 outwardly and downwardly, the lower portion of the door will be moved out of the doorway. 50

What is claimed is:

1. The combination with a car wall and its doorway and track thereabove, of a door having means arranged to move the same into and out of the doorway, hangers on the track, vertically disposed bars, means on the door for maintaining the bars in slidable engagement with the door, links connecting the hangers and bars, certain of the maintaining means being formed to permit pivotal movement of the door and links, stops on the bars, and means on the door for engagement with the stops to limit the relative movement of said door and bars. 55

2. The combination with a car wall having a doorway and a track thereabove, of hangers on the track, a door, vertically aligned loops on the door, the uppermost of the loops being longer than the others, a transverse bar fixed on the lower portion of the door, vertical bars slidable through the loops and beneath the transverse bar, links hinged to the lower ends of the hangers and to the upper ends of the bars, the hangers being arranged to play in the longer loops 70 upon movement of the door into and out of the doorway, and outwardly extending projections on the lower ends of the vertical bars for engagement by the transverse bar to limit the downward movement of the door. 75 80

In testimony whereof we affix our signatures in the presence of two witnesses.

ANGUS R. COOPER.
HUGH J. CARTHY.
